TRAVELING WAVE ANTENNA

Nils E. Lindenblad, Rocky Point, N. Y., assignor
to Radio Corporation of America, a corpora-
tion of Delaware

Application November 11, 1944, Serial No. 562,983

10 Claims. (Cl. 250—33.51)

1

The present invention relates to traveling wave antennas and, more particularly, to long wire traveling wave antennas.

An object of the present invention is to improve the efficiency of traveling wave antennas.

Another object of the present invention is the provision of a directive antenna which is substantially aperiodic over a wide band of frequencies.

Still another object of the present invention is the provision of an aperiodic antenna which is selectively directive in opposite directions.

A further object of the present invention is the provision of a traveling wave antenna which may be simply switched for selective directivity in a pair of opposite directions.

Still a further object of the present invention is the provision of a traveling wave antenna having a low characteristic impedance.

Still a further object of the present invention is the provision of a traveling wave antenna and an unbalanced transmission line system which may be directly connected together without the interposition of reactance circuits.

The foregoing objects are attained by providing a traveling wave antenna in the form of a large diameter cage. The transmission lines associated with the antenna are constructed in the form of large diameter coaxial lines having their outer conductor in the form of a cage similar to the cage forming the antenna. In some cases the antenna itself may form at least a part of the coaxial cage transmission line system for energizing the antenna.

The invention will be more fully understood by referring to the following detailed description which is accompanied by a drawing in which Figure 1 illustrates in simplified diagrammatical form an embodiment of the invention, while Figure 2 illustrates a modified form of the invention.

Figure 1 illustrates a two-way traveling wave antenna in which the transmitter is located at a point intermediate the ends of the antenna. The antenna itself is denoted by reference character 10. Antenna 10 is in the form of a cage, being constructed of a plurality of wires 11 arranged longitudinally on the surface of an imaginary cylinder. The cylindrical formation is maintained by circularly arranged supports. Antenna 10 has an overall length of preferably at least one wavelength at the operating frequency. It is supported a short distance above ground by suitably arranged poles spaced along the length of the antenna. The supporting structure is not

2

shown in Figure 1, since conventional telephone poles may be used.

As an actual example, the antenna when operating at a frequency of about 1.6 megacycles may have an overall length of about 1200 feet and be supported from 12 to 15 feet above the ground. The antenna may have a diameter of the order of 5 feet. A convenient form of construction utilizes as much as six parallel wires in the cage when the soil resistivity is very low. Thus the characteristic impedance of the antenna may be as low as of the order of 200 ohms. However, when the resistance of the soil over which the antenna is erected is moderately high or higher, a lesser number of wires becomes more efficient. Each end of antenna 10 is arranged to be selectively energized by a transmitter T located intermediate the ends of the antenna. The end of the antenna opposite to the end to which the transmitter is connected is grounded through a terminating resistor R. Resistor R preferably has a resistance equal to the surge impedance of the antenna for which condition energy arriving thereat is absorbed at the rate of arrival and is hence dissipated without reflection. Thus a traveling wave is set up in the antenna, travelling only from transmitter T to resistor R and having a cumulative radiation effect only in the direction off the end to which resistor R is connected. This cumulative radiation effect originates with the charge displacements taking place in the soil-dielectric-medium. A double-pole, double-throw switch as indicated by 15 at the transmitter location selects the direction of transmission. The ends of antenna 10 are brought to the transmitter location by transmission lines 20 and 30. Each transmission line includes an inner-conductor 21 surrounded by a cage outer conductor 22. The cage outer conductor 22 is formed of parallel wires 23 arranged about supporting rings 24 in a manner similar to the manner of construction of the antenna 10. The ratio of cage diameter to the diameter of the inner conductor is so chosen as to give a characteristic impedance equal to the characteristic impedance of antenna 10. Preferably, each of the transmission lines 20 and 30 is grounded at each support, as indicated, by wires 26 running from the support rings 24 to conventional ground symbols. The ground at the antenna input end should be extra good.

Now when switch 15 is thrown, for example, to the right hand position as indicated by reference character E, resistor R is connected to the right hand end of antenna 10 and the transmitter

T to the left hand end. Maximum radiation will then be attained off the right hand end of the antenna as indicated by the arrow labeled E. Similarly, if switch 15 is thrown to the left hand position as indicated by reference letter W, resistor R is connected from the left hand end of the antenna 10 to ground and the transmitter T is connected from the right hand end of antenna 10 to ground. Maximum radiation is thereby attained off the left hand end of antenna 10 as indicated by arrow W.

Under some circumstances it may be desirable to locate the transmitter associated with a traveling wave antenna near one end of the antenna rather than intermediate the ends as shown in Figure 1. If such is the case, the modification shown in Figure 2 may be used.

In Figure 2, the antenna comprises an outer case structure similar to the cage shown in Figure 1 and in which the corresponding parts of the antenna bear corresponding numbers. That is, each of the parallel wires of the antenna are identified by reference numeral 11 and the support for the cage are identified by reference character 12. However, in this modification the antenna 10 forms also a part of the transmission line structure for selectively energizing the antenna for radiation in a pair of alternate directions. For this purpose, an inner conductor 40 passes through the entire length of the antenna. At one end conductor 40 is directly and thoroughly grounded; while at the other end it passes into an extension cage transmission line member 50 which should be of relatively small length. At the free end of the transmission line 50 the outer conductor cage of the transmission line is connected to transmitter T and resistor R. The inner conductor 40 is connected to a pair of contacts on double-pole, double-throw switch 15 while another pair of contacts on switch 15 are connected together and to ground. The moving arms of switch 15 are connected to the transmitter T and resistor R. Thus when the switch 15 is thrown to the right hand position, at E, the transmitter T is directly connected between the inner conductor 40 and the outer cage of the transmission line 50. Also resistor R is connected from the end of the outer cage 50 to the ground connection. Thus energy from transmitter T is conducted through the transmission line 50 and through the interior of antenna 10 acting as a transmission line to the remote end of the antenna. There the energy flows back over the outer surface of antenna 10 and is radiated in the conventional manner. Energy traveling the entire length of antenna 10 and the entire length of the outer surface of transmission line 50 is dissipated to ground through resistor R. Thus maximum radiation is obtained in the direction of arrow E. Now if switch 15 is thrown to the left hand position, at W, the transmitter T is connected from the outer casing of transmission line 50 to the ground which should be adequate for this purpose while the resistor R is connected between the outer casing and conductor 40. With this connection, the energy from transmitter T flows along the outer surface of transmission line 50 along the outer surface of antenna 10. That which is not radiated by the time it reaches the free end of antenna 10 is conducted back through the interior of antenna 10 and along conductor 40, acting as the inner conductor of a coaxial transmission line, back to the transmitter location where it is dissipated across resistor R. With this connec-

tion the maximum radiation takes place toward the left in the direction indicated by arrow W.

While I have illustrated a particular embodiment of the present invention, it should be clearly understood that it is not limited thereto since many modifications may be made in their arrangement and it is therefore contemplated by the appended claims to cover any such modifications as fall within the spirit and scope of the invention.

What I claim is:

1. A traveling wave antenna including an elongated conductor having an overall length equal to at least one wavelength at the operating frequency, said conductor being constructed in the form of a wire cage, means for selectively electrically connecting a source of high frequency energy to either end of said conductor, and means for electrically connecting a terminating resistor to the other end, said source and said terminating resistor being located adjacent one another.

2. A traveling wave antenna including an elongated conductor having an overall length equal to at least one wavelength at the operating frequency, said conductor being constructed in the form of a wire cage, means for selectively electrically connecting a source of high frequency energy to either end of said conductor, and means for electrically connecting a terminating resistor to the other end, said source and said terminating resistor being located adjacent one another, said connecting means including a coaxial transmission line having an inner conductor and an outer conductor in the form of a wire cage.

3. A traveling wave antenna including an elongated conductor having an overall length equal to at least one wavelength at the operating frequency, said conductor being constructed in the form of a wire cage, means for selectively electrically connecting a source of high frequency energy to either end of said conductor, and means for electrically connecting a terminating resistor to the other end, said source and said terminating resistor being located adjacent one another, said connecting means including a coaxial transmission line having an inner conductor and an outer conductor in the form of a wire cage, the ratio of the diameters of said inner conductor and said outer conductor being so chosen that the characteristic impedance of said transmission line is equal to the impedance of said antenna.

4. A traveling wave antenna including an elongated conductor having an overall length equal to at least one wavelength at the operating frequency, said conductor being constructed in the form of a wire cage, means for selectively electrically connecting a source of high frequency energy to either end of said conductor, and means for electrically connecting a terminating resistor to the other end, said source and said terminating resistor being located adjacent one another, said connecting means including a coaxial transmission line having an inner conductor and an outer conductor in the form of a wire cage, the ratio of the diameters of said inner conductor and said outer conductor being so chosen that the characteristic impedance of said transmission line is equal to the impedance of said antenna, said antenna cage forming at least a portion of the outer conductor of said transmission line.

5. A selectively bi-directional antenna including a wire cage conductor having an overall length equal to at least one wavelength at the operating frequency, a transmission line having

an outer conductor in the form of a cage connected to said first-named cage at one end and an inner conductor passing through the length of said transmission line and said antenna cage, said inner conductor being grounded at the far end, a source of high frequency and a terminating resistor connected to an end of the other conductor of said transmission line, a ground connection, and means for selectively connecting said source of high frequency to said inner conductor and the other end of said terminating resistor to the ground connection, or vice versa.

6. A selectively bi-directional antenna including a wire cage conductor having an overall length equal to at least one wavelength at the operating frequency, said wire cage having its transverse dimension so chosen with relation to the height of said antenna above ground as to give a low characteristic impedance, a transmission line having an outer conductor in the form of a cage connected to said first-named cage at one end and an inner conductor passing through the length of said transmission line and said antenna cage, said inner conductor being grounded at the far end, a source of high frequency and a terminating resistor connected to an end of the outer conductor of said transmission line, a ground connection, and means for selectively connecting said source of high frequency to said inner conductor and the other end of said terminating resistor to the ground connection, or vice versa.

7. A selectively bi-directional antenna including a wire cage antenna having an overall length equal to at least one wavelength at the operating frequency, a transmission line having an outer conductor in the form of a cage connected to said first-named cage at one end and an inner conductor passing through the length of said transmission line and said antenna cage, said inner conductor being grounded at the far end, a source of high frequency energy connected between the inner and outer conductors of said transmission line and a terminating resistor connected between said outer conductor and ground.

8. A selectively bi-directional antenna including a wire cage antenna having an overall length equal to at least one wavelength at the operating frequency, a transmission line having an outer conductor in the form of a cage connected to said first-named cage at one end and an inner conductor passing through the length of said transmission line and said antenna cage, said inner conductor being grounded at the far end, a terminating resistor connected between the inner and outer conductors of said transmission line, and a source of high frequency energy connected between said outer conductor and ground.

9. A selectively bi-directional antenna including a wire cage conductor having an overall length equal to at least one wavelength at the operating frequency, a pair of transmission lines each having an outer conductor in the form of a cage, and an inner conductor, one end of each of said transmission lines being electrically connected to an end of said antenna, the other ends of said transmission lines being closely adjacent, a source of high frequency energy and a terminating resistor, and means for selectively electrically connecting said source to either of said transmission lines and said resistor to the other of said transmission lines.

10. A selectively bi-directional antenna including a wire cage conductor having an overall length equal to at least one wavelength at the operating frequency, a pair of transmission lines each having an outer conductor in the form of a cage and an inner conductor, the ratio of diameters of said outer conductors to said inner conductors being so chosen as to give a characteristic impedance equal to the impedance of said antenna, one end of each of said transmission lines being electrically connected to an end of said antenna, the other ends of said transmission lines being closely adjacent, a source of high frequency energy and a terminating resistor, and means for selectively electrically connecting said source to either of said transmission lines and said resistor to the other of said transmission lines.
